PROJECTING DEVICE FOR TOY AIRPLANES

Selig Oppenheim and Karl Kouba, Chicago, Ill.

Application February 23, 1940, Serial No. 320,307

4 Claims. (Cl. 124—21)

This invention relates generally to amusement devices and more particularly to a catapult or projector for launching toy airplanes or the like into flight.

The main object of this invention is to provide a new and improved construction for a toy catapult which will be sturdy and rugged, and efficiently adapted for the purposes to which it is directed.

A further object of the invention is to provide, in a device of the character described, a novel means for attaching and maintaining the propulsion means in a highly advantageous manner.

Still a further object of the invention is to provide, in a device of the character described, utilizing extensible propulsion means, novel means for adjusting the projection tension of said extensible propulsion means.

Still a further object of the present invention is to provide, in a device of the character described, a novel shuttle or carrier for projecting a miniature airplane into flight.

A further object of the present invention is to provide a novel guiding means for the shuttle of our improved launching catapult.

Further objects of the invention reside in providing a novel shock absorbing means for my shuttle, providing means associated with said shuttle for drawing same into position prior to release, providing novel means for attaching an extensible propulsion means to our device.

With the foregoing and other objects in view, which will appear as the description proceeds, the invention consists in certain novel features of construction, arrangement and combination of parts hereinafter fully described, illustrated in the accompanying drawing, and particularly pointed out in the appended claims, it being understood that various changes in the form, proportion, size and minor details of the structure may be made without departing from the spirit or sacrificing any of the advantages of the invention.

For the purpose of facilitating an understanding of our invention, we have illustrated in the accompanying drawing a preferred embodiment thereof, from an inspection of which, when considered in connection with the following description, our invention, its mode of construction, assembly and operation, and many of its advantages should be readily understood and appreciated.

Referring to the drawing in which the same characters of reference are employed to indicate 55

corresponding or similar parts throughout the several figures of the drawing:

Fig. 1 is a side elevational view of our new catapult with portions thereof in section.

Fig. 2 is a plan view of our improved catapult.

Fig. 3 is a front elevational view of our catapult.

Fig. 4 is a transverse sectional view taken along the line 4—4 of Fig. 1.

10 Referring to specific details of construction and arrangement of parts, the reference character 10 designates generally a substantially L-shaped member of wood, or other suitable material, forming the body of our catapult.

15 A portion of said body 10 comprises the handle or grip 11 adapted to be grasped by the operator in the manner of a pistol, but obviously same could be constructed to operate as a rifle by providing the body with a stock to the rear of grip

20 11. The barrel 12 of the member 10 is generally rectangular in cross section, as shown in Fig. 4, with the bottom thereof rounded to promote comfort in handling. The forward portion of the barrel 12 is flared as shown at 13 and is

25 notched as at 14 for a purpose presently to be described. Immediately above the flared portion 13 and the grip 11, there are provided upstanding extensions 15 and 16, respectively, said extensions being integrally formed with the body 10

30 of the catapult. A rod member 17 extends between said extensions 15 and 16 for the purpose of guiding the motion of the shuttle, designated generally by the character 18. Said rod member 17 is fixed in position by any appropriate means, such as providing one end with a head 19 and threading the other end to receive nut 20, with associated washers and the like, or by any other convenient means.

Thus it will be observed that the forward and 40 rearward motion of the shuttle 18 is confined to the space between the extensions 15 and 16. In order to more accurately guide the shuttle member 18, the body 10 is provided between the extension portions 15 and 16 with a rectangular

45 groove 21. Said groove 21 provides the track for a correspondingly shaped tongue or extension 22 provided on the bottom of the shuttle 18 whereby the shuttle may be guided by the groove 21 as well as the rod member 17.

50 The shuttle member 18 is provided with an opening 23 longitudinally thereof in order to accommodate the rod member 17. A second opening 24 passes through the shuttle perpendicularly to the line of flight (which obviously is right and left as viewed in Fig. 1) and has

the ends thereof countersunk in order to eliminate wear of the propulsion means 25. Said propulsion means consists of a strand or group of strands of flat rubber, or the like, but may be any elastic extensible device which can be adapted for the purpose herein described. The propulsion band extends from the shuttle 18 to the two openings 26 provided in the arms of a generally Y-shaped member 27 which is fixed to the forward end of the barrel 12 by means of screws 28 or the like. We prefer that the member 27 should be formed from a shock withstanding material, such as a phenol plastic, especially where the body 10 of the catapult is of wood. It is to be noted that the member 27 may be firmly attached by reason of the flared portion 13 providing ample room for strong screws or other fastening means. In our illustrated embodiment, the head 19 of the rod member 17 aids in maintaining the member 27 in place.

The propulsion band 25 passes through the openings 26, between the arms of the Y-shaped member 27, and passes to the opening 24 in the shuttle. Where the member 25 has been formed by joining the free ends of strand or strands, the joining knot or splice is best positioned within the opening 24. If it is desired to increase the propulsion tension of the band 25, the front portion thereof which extends between openings 26 may be stretched downward to engage the notch 16 on the underside of the flared portion 13 as shown by broken lines of Fig. 1. While only one notch is disclosed, it is obvious that a plurality of such notches will increase the tension adjustability of the member 25.

The shuttle member 18 is pulled rearward, when it is desired to operate the catapult, by grasping the portion 29 provided therefor on the upper side of the shuttle and moving same to the right as viewed in Fig. 1. This motion tensions the band 25 so that if released the shuttle will snap to the left. The grip 11 is provided with a trigger member 30 pivoted at 31, having a hook portion 32 with a rounded forward face 33 and a sharp-cornered rearward face 34. The hook portion 32 projects through a passage 35 provided therefor in the barrel 12, and is disposed in the groove 21 in the path of the shuttle 18. The spring 36 provided in the grip cavity 37 engages the trigger member 30 at the projection 38 and normally tends to force the trigger member 30 in a clockwise direction about the pivot pin 31, thus keeping the upper end of the hook portion 32 in the position shown in Fig. 1.

When the shuttle 18 is moved to the right, the corner 39 of the tongue 22 engages the rounded portion 33 of the hook 32 thereby depressing the trigger member 30 against the tension of the spring 36 while the shuttle is moved past the hook portion 32. However, as soon as the shuttle passes the opening 35, the hook springs back into position so that the corner 34 engages and holds the front corner of the shuttle preventing the tension of the member 25 from pulling same forward.

When it is desired to release the shuttle 18, pressure on the finger portion 40 of the trigger member will move the portion out of the path of the shuttle, causing same to fly forward for obvious reasons.

In order to prolong the life of our catapult and minimize the shock caused by the shuttle striking the portion 15 after traveling its path, we provide shock absorbing means, comprising a coiled spring member 41 disposed on the forward end

of the rod member 17. Washers are associated therewith in any convenient arrangement. Besides the shock absorbing advantages of the member 41, the elimination of shock from the shuttle 5 at the end of its stroke will prevent breakage and misadjustment of the airplane 42 or other device carried by the shuttle 18.

The airplane which is adapted to be used in connection with our catapult is a simple one, comprising a single fuselage member 43, weight at its front end 44, and having a horizontally disposed wing 45, horizontal tail member 46 and vertical rudder 47. For the accommodation of the plane 42 in an efficient manner which will eliminate 10 the need for any special appliances being attached either to the plane or the shuttle 18, we provide the shuttle with a group of forwardly extending fingers adapted to firmly engage the tail assembly of the airplane 42. Said fingers are four 15 (4) in number in order to accommodate an airplane of the form illustrated, but obviously the number may be increased or decreased in accordance with the construction of the airplane which it is desired to launch.

20 The fingers 48, 49, 50 and 51 are separated vertically in order to accommodate the tail member 46. They are also separated horizontally slightly more than vertically in order to accommodate the fuselage member 45 and permit the vertical rudder 47 to protrude between fingers 48 and 49.

25 It will thus be seen that the airplane 42 is adapted to be firmly held in the shuttle and yet be free to be launched forward when the catapult is operated. The broken lines of Fig. 1 show the shuttle with the airplane 42 associated therewith poised prior to release of the shuttle by trigger in a manner described. The solid lines show the shuttle and airplane at the extreme 30 left end of the path of the shuttle before the same had been drawn back to the position shown in broken lines. It is obvious how the device operates and hence further explanation will be dispensed with.

35 It is believed that our invention, its mode of construction and assembly and many of its advantages should be readily understood from the foregoing without further description, and it should also be manifest that while a preferred 40 embodiment of the invention has been shown and described for illustrative purposes, the structural details are nevertheless capable of wide variation within the perview of our invention as defined in the appended claims.

45 What we claim and desire to secure by Letters Patent of the United States is:

1. A device of the character described comprising an elongated substantially L-shaped member arranged so that one leg thereof forms a grip 50 and the other leg forms the barrel portion of a catapult, an elongated recess provided in the top edge of the barrel portion and being blocked off at either end thereof, and defining thereby a track within which a shuttle is adapted to be 55 disposed, an elongated rod member disposed within said recess and extending between the ends thereof, a perforated shuttle slidably mounted on said rod through the perforation thereof and adapted to slide in said track, an extensible 60 member attached to the forward end of said barrel portion and also being attached to said shuttle whereby when said shuttle is moved to one end of said track adjacent said grip portion of said L-shaped member said extensible member will tend to pull said shuttle forward in said 65 70 75

track, and trigger means releasably holding said shuttle in said last mentioned position and against the tension of said extensible member, said rod member having a shock absorbing spring associated therewith at the forward end thereof for cushioning the shuttle as it reaches the forward end of the recess in its forward motion.

2. A device of the character described comprising an elongated substantially L-shaped member arranged so that one leg thereof forms a grip and the other leg forms the barrel portion of a catapult, an elongated recess provided in the top edge of the barrel portion and being blocked off at either end thereof, and defining thereby a track within which a shuttle is adapted to be disposed, an elongated rod member disposed within said recess and extending between the ends thereof, a perforated shuttle slidably mounted on said rod through the perforation thereof and adapted to slide in said track, an extensible member attached to the forward end of said barrel portion and also being attached to said shuttle whereby when said shuttle is moved to one end of said track adjacent said grip portion of said L-shaped member, said extensible member will tend to pull said shuttle forward in said track, and trigger means releasably holding said shuttle in said last mentioned position and against the tension of said extensible member, said rod member having a shock absorbing spring associated therewith at the forward end thereof for cushioning the shuttle as it reaches the forward end of the recess in its forward motion, and an outwardly extending cross member attached to the forward end of the L-shaped member and having the forward portion of the extensible member attached to the outer ends thereof whereby upon forward movement of the shuttle tangling of the extensible means will be eliminated and the full stroke of the shuttle will be powered by contraction of said extensible means.

3. A device of the character described comprising an elongated member, means associated with said member for launching a projectile therefrom, said means including a shuttle reciprocable upon said member and adapted to carry said projectile while imparting its initial velocity thereto, pro-

40 pulsion means for driving said shuttle in its reciprocatory movement, said elongated member having upwardly extending portions at opposite ends thereof extending into the path of said shuttle to the front and rear thereof and thereby defining the limits of travel of said shuttle, a track being provided on said elongated member between said upwardly extending portions, said shuttle having a portion thereof riding in said track and prevented thereby from lateral movement therein, an elongated rod member extending between said upwardly extending portions, said shuttle being provided with a central opening through which said rod member passes, and cooperating means between said track and shuttle preventing said shuttle from wobbling, laterally moving or rotating about said rod member during its longitudinal motion.

4. A device of the character described comprising an elongated member of substantially L-shaped formation, one of the legs comprising a grip portion and the other of said legs being elongated and comprising a barrel portion, upstanding portions integrally formed with said L-shaped member and provided on the upper edge of said barrel portion, a groove formed in said barrel in the upper edge thereof between said upstanding portions and adapted to receive a tongue therein, a single metal rod extending substantially the length of said barrel portion and having its ends secured to said upstanding portions and disposed in the space between said upstanding portions, a shuttle having a portion thereof riding in said groove and being of tongue-like cross-section, said 45 shuttle having a longitudinally extending perforation adapted to be threaded by said rod to confine, and guide said shuttle during its reciprocatory motion, an elastic band attached to the forward portion of the barrel and to said shuttle and normally tending to pull said shuttle in a forward direction, and trigger means provided in said barrel portion cooperating with said shuttle to releasably hold same in a poised condition against the pull of said elastic band.
